UNITED STATES PATENT OFFICE.

JOHN SLATER, OF BURSLEM, ENGLAND.

DESIGN FOR A DISH.

SPECIFICATION forming part of Design No. 21,309, dated January 19, 1892.

Application filed December 28, 1891. Serial No. 416,877. Term of patent 3½ years. Registered in England March 21, 1891, No. 168,550.

To all whom it may concern:

Be it known that I, JOHN SLATER, a subject of the Queen of Great Britain, residing at Burslem, Staffordshire, England, have invented a certain new and original Design for Dishes, fully described and represented in the following specification and the accompanying drawings, forming a part of the same, the said design being embraced in registration in Great Britain, dated March 21, 1891, number on register 168,550.

In the accompanying drawings, forming a part of this application, the design of the present invention is for convenience illustrated in connection with a covered dish; but it is to be understood that it is equally applicable to coverless or any other dish of a table-service.

In said drawings, Figure 1 represents by a side view a covered dish embodying the design of the present invention. Fig. 2 is a plan view of the cover removed from the body of the dish; and Fig. 3 is a bottom view, partly in perspective, of the body of the dish.

The essential characteristics of the design are as follows: The body of the dish shown is oblong in cross-section and is slightly depressed at each end. It is provided with a plurality of depressions *a*, equidistant or substantially equidistant from each other and forming corrugations *b*, the depressions *a* and corrugations *b* extending downwardly from the upper edge of the dish and then inwardly under the bottom of the dish to a point at or, as shown, near the center of the bottom of

the dish, (see Fig. 3,) the corrugations *b* having their greatest depth and width at the upper edge of the dish and gradually contracting as they approach the center of the bottom of the dish. The dish may be provided at each end with a handle *c*, corrugated transversely, as shown. The cover of the dish has a contour corresponding, horizontally considered, to that of the body of the dish. The cover also, like the body of the dish, is slightly depressed at each end and is provided with depressions *a* and corrugations *b*, forming continuations of the depressions and corrugations in the body of the dish. The depressions *a* and corrugations *b* of the cover, however, terminate at the base of a panel *d*, formed in the center of the cover. The cover may be provided with a handle *c*, located upon the panel *d* and corrugated transversely, as in the case of the handles upon the body of the dish.

What is claimed is—

1. The design for a dish, substantially as herein shown and described.
2. The design for the cover of a dish, substantially as herein shown and described.

In testimony whereof I have hereunto set my hand in the presence of two subscribing witnesses.

JNO. SLATER.
